G. S. Appleton

UNITED STATES PATENT OFFICE.

GILES S. APPLETON, OF BURLINGTON, VERMONT.

RAILROAD SAFETY-SWITCH.

Specification of Letters Patent No. 22,844, dated February 8, 1859.

To all whom it may concern:

Be it known that I, GILES S. APPLETON, of Burlington, in the county of Chittenden and State of Vermont, have invented certain new and useful Improvements in Switches for Railroads; and I do hereby declare that the following is a full, clear, and exact description thereof, reference being had to the accompanying drawings, and to the letters of reference marked thereon, forming a part of this specification.

To enable those skilled in the art to which my invention belongs to make and use the same, I will now proceed to describe it.

Figure 1, is a perspective view and Fig. 2, is a cross section of the switch and traverse rails in the line α , α , Fig. 1.

n , n , are the permanent rails of a single track, and A, B, C, A', B', C', are the permanent rails of three tracks.

E, E', are two long switch rails. These rails are pivoted at h , h' , or otherwise held by a flexible joint, which will permit of their being vibrated on a point near the permanent track n , n , as shown in Fig. 1. These rails where they meet the permanent rails n , n' , are of about the same width of an ordinary rail, and are of the same height as the rails n , n' . As they extend however toward the permanent rails A, B, etc., they widen so that at their middle their top surfaces present a broad, flat and even surface, as shown in Fig. 2. The ends of these rails next the rails A, B, etc., are grooved out

for a very short distance, the grooves being deepest at the widest ends of the rails E, E'. These grooves are seen at 1, 2, and 1', 2'. After these grooves are made, there appear short elevations, which resemble rails, between the grooves, as seen at a , b , c , and a' , b' , c' . These grooves all terminate at the top of the rails E, E', and at a short distance from their widest ends, as fully shown in Fig. 1.

The switch rails E, E', in addition to being pivoted or hinged at h , are fastened to wide cross-bars G, G', by bolts or pins.

Upon the inside of the switch rails E', E, are placed the traverse rails F, F'. These traverse rails resemble somewhat the switch rails E, E', inasmuch as they are narrow at the ends nearest the rails n , n' , and gradually wider toward their opposite ends. These traverse rails are fastened to the wide cross bars G, G', in such a manner that an open space is left between them and the rails

E, E', of sufficient width to allow of the flange of a wheel to pass along and between the rails E, E', and F, F', while the tread of the wheels rests on and moves along upon the tops of the rails E, E'. This opening is seen at l , l' , Figs. 1, and 2, and extends from top to bottom, the entire length of the rails F, F'.

The traverse rails F, F', are provided on their inner and top sides with guards or rails H, H', which extend their entire length as shown in Fig. 1. They are also provided with short guide or guard rails e, e', which extend about the same distance as the grooves in the switch rails E, E'. The guide or guard rails e, e', are just sufficiently far from the guard rails H, H', to permit of the flange of the wheels to pass between them in the groove g , or g' , while the tread of the wheel rests upon the short rails e, e'. The rest of the traverse rails F, F', have smooth and even surfaces, as seen at f , f' , Figs. 1, and 2. This surface rises toward the ends m , m' .

The traverse rails F, F', being fastened to the wide cross bars or supports G, G', to which the switch rails E, E', are attached, are moved by the same means and at the same time as the switch rails, and have the same center of motion or nearly so.

The wide and sliding ends of both the switch and traverse rails rest and slide upon the plates D, D'. These plates D, D', have their ends turned up as shown in Fig. 1, at 3, 3, and 3', 3', so that the extreme extent which the rails can be moved in either direction, is governed by the rising ends 3, 3', of the plates D, D'.

The switch may be moved and locked in any desired position by any of the well known devices now in use for moving and locking switches.

The operation is as follows: If a train of cars pass over the track in the direction of the arrow 1, and the switch be in the position shown in the drawings Fig. 1, then the cars would pass from the track or rails n , n' , over the switch rails and on to the rails C, C'. Now if while the switch is in the position shown, a train pass in the direction of arrow 2, on the rails A, A', it will not be thrown off of the track, since the flanges of the wheels on one side of the cars, will pass into the short inclined groove i , in the wide end of the switch rail E, while the flanges of the wheels on the other side of the

cars, will pass into the groove g' , on the traverse rail F' . The wheels are thus guided upon to the broad faces of both the switch and traverse rails and as they continue to move on, the guard rail H' , in connection with the surface of F' , direct the cars in a gentle and easy manner toward the switch rail E' , until at the point o , o , the flanges of the wheels drop between the switch and traverse rails, and the tread of the wheels, on the switch rails E , E' , when the cars pass without difficulty on to the single track or rails n , n' . Should a train pass in the direction of the arrow 2, on the rails B , B' , it would be directed on to the rails n , n' , in a similar manner, with the exception that the flanges of the wheels on one side of the cars would pass in the short groove 2, while those on the other side of the cars would pass on to the smooth and even face f' , of the traverse rail F' . The wheels of the cars would, however, be guided on to the smooth surface or face of the switch and traverse rails F' , and E , and from thence, as before described, on to the rails n , n' . It will thus be seen that it is impossible for a train to run off the track. If a train pass in the direction of arrow i , in whatever position the switch may be locked, it cannot run off the track, for if the switch be wrong, the train will run upon some one of the tracks, and thus give the engineer time to stop his train. Neither can a train be thrown off in passing on either of the tracks in the direction of arrow 2, for, as before described, if the switch be wrong, the train will pass without danger over the switch and on to the rails, n , n' . It is often the case on many of our Northern roads that six or eight different tracks run together so that the trains from each have to pass on to a single track. In these cases, owing to the switches used, getting out of order, or being left locked in a wrong position—numerous accidents are continually occurring. Again in those switches, which have been devised for avoiding these accidents, it is found that the long and severe winters of the North, have not been duly considered, since the construction of such switches, is of such a character, as to render them almost useless by reason of the snow and ice getting into the working parts of the switches &c. I have therefore been led from a practical test of these switches, under the circumstances above alluded to, to devise a switch which, while it should be simple and effective, it should at the same time, be of such a construction as not to be easily affected by snow and ice. I have also found that there is less liability of a train's being thrown off, when passing over a misplaced switch, if the wheels are allowed some considerable lateral play, inasmuch as when they are closely confined,

any little obstruction is liable to make them jump the guards and leave the track. By my construction and arrangement this object is effected, while at the same time and by the same construction and arrangement, the switch is made self cleaning &c.

By reference to Fig. 1, it will be seen that the grooves in the switch rails E , E' , extend but a short distance, so that the wheels are left to traverse the smooth surfaces of the 75 traverse and switch rails for some distance after leaving the short grooves, and that while so traversing, they are allowed considerable lateral play. By having the upper surfaces of the rails E , E' , smooth, and allowing the wheels to have a lateral motion on the same, the ice is cut up and thrown off the rails. In this way the switch is made a self cleaning one, but should the ice accumulate too fast, to be cleaned away by passing trains, it would require but a short time, owing to the simple construction of the switch, for a man to clean it way with a pick or shovel.

It will be noticed that any number of 90 tracks can be used by simply widening the switch and traverse rails.

Another great advantage of this switch consists in the fact, that in its first construction it would cost but little more to make 95 one for six or eight tracks, than it would for three, and that one made for six or eight can be used for two or three just about as well as if made for two or three only. Again it will be noticed, that the 100 traverse rails F , F' , are somewhat lower than the switch rails E , E' , and that the relative arrangement of these rails is such, that the flanges of the wheels on one side of the cars (when the switch is misplaced) will 105 always run upon one of the traverse rails, while those on the other side of the cars will always run on one of the switch rails. By this arrangement, owing to the traverse rails being a little lower than the switch rails, the cars are inclined toward the right track, whereby much strain and wear on the guard rails H , H' , is avoided. It will also be noticed that by my arrangement the wheels are permitted to pass in varying paths after 110 they reach the tops of the switch and traverse rails, and thus are permitted to vary their line of motion to suit varying circumstances.

However great the number of the side 115 tracks, no additional short guards e , e' , need be added to the traverse rails F , F' , all that is necessary being to simply cast or form the surfaces f , f' , wider.

The switch rails E , E' , are cast or made 125 of such relative width as that they will always extend some distance beyond the flanges of the wheels when the opposite flanges are close up against the guard rails H , H' .

Having described my improved switch, what I claim as new and of my invention, and desire to secure by Letters Patent, is—

1. The combination of the broad and even switch rails E, E', with the broad and even traverse rails F, F', long guide rails H, H', and short lift and guide rails a, b, c, and a', b', c', when the same are arranged in relation to each other substantially as shown 10 and described.

2. Allowing the wheels to play upon the wide traverse and switch rails, after leaving the short lift ways and guide rails, and before they reach the main track substantially in the manner and for the purposes above described. 15
